UNITED STATES PATENT OFFICE

101,004

DESIGN FOR A WHEEL DISK OR SIMILAR ARTICLE

George Albert Lyon, Detroit, Mich.

Application January 15, 1936, Serial No. 60,607

Term of patent 14 years

To all whom it may concern:

Be it known that I, George Albert Lyon, a citizen of the United States, and residing in the city of Detroit, in the county of Wayne and State of Michigan, have invented a new, original, and ornamental Design for a Wheel Disk or Similar Article, of which the following is the specification, reference being had to the accompanying drawing forming a part thereof.

On the drawing:

Figure 1 is an outer side view of a wheel disk

having a high lustrous light-reflecting finish and embodying my design.

Figure 2 is a side elevational view of the disk shown in Figure 1.

Figure 3 is a profile view showing in outline form the contour of my novel design of disk.

I claim:

The ornamental design for a wheel disk or similar article, as shown and described.

GEORGE ALBERT LYON.
